INVENTOR,
JOSEPH D. BELL.
BY ATTORNEY.

UNITED STATES PATENT OFFICE

JOSEPH D. BELL, OF SAN FRANCISCO, CALIFORNIA

EXERCISING MACHINE

Application filed June 19, 1929. Serial No. 372,020.

The invention relates to exercising devices.

The primary object of the invention is the provision of an exercising device in which a rocking movement of a seat supporting frame and a rotary movement of a rotary member of the device is caused either by the shifting of the weight on the rocking frame or by the rotation of said member.

Another object of the invention is the provision of an exercising device in which a seat is mounted on a rocking frame, on a tricycle-like mechanism, so as to rock about a horizontal axis; the rocking frame being operatively connected to the traction wheels of the tricycle-like mechanism, so as to produce a simultaneous rocking of the frame and the rotation of the wheels by the shifting of the weight on the rocking frame.

Another object of the invention is the provision of an exercising device in which a seat is mounted on a rocking frame, which in turn is mounted on the main frame of the tricycle; the traction wheels of the tricycle being connected by a train of gears to suitable cranks, which latter are so connected to the rocking frame that the rocking of the rocking frame causes the turning of the crank thereby rotating the traction wheels, in other words, the rotation of the wheels and the rocking of the rocking frame is produced simultaneously by the same motive force, means being provided to prevent the traction of the wheels, so as to support the device in one place at will.

Other objects and advantages are to provide an exercising machine that will be superior in point of simplicity, inexpensiveness of construction, positiveness of operation, and facility and convenience in use and general efficiency.

In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawings in which—

Fig. 1 is a side elevation of the exercising device;

Fig. 2 is a fragmentary plan view of the rear end of the device;

Fig. 3 is a side elevation of a modified form of the rear end of the device;

Fig. 4 is a fragmentary detail view of a support for the traction wheels of the device;

Fig. 5 is a side view of a modified form of the device, in which the traction wheels are the front wheels;

Fig. 6 is a plan view of the device shown in Fig. 5;

Fig. 7 is another embodiment of the exercising device; and

Fig. 8 is a fragmentary detail view of an embodiment of the device, in which the leverage of the rocking frame is adjustable.

In carrying out my invention I make use of tricycle-like mechanism A, upon which is rockably mounted a rocking frame B.

The mechanism A is assembled on a main frame 6, the rear end of which is formed in the shape of a loop 7, from which extend outwardly, bearing 8. An axle 9 is rotatably supported in the bearings 8. Upon each end of the axle 9 is fixedly mounted a rear wheel 11 of the tricycle, so as to rotate with the axle 9. The axle 9 has a gear 12 fixedly attached thereto, within the loop frame 7. In said loop frame 7 are also journaled gears 13 and 14 in mesh with each other. The gear 13 and the gear 12 are also in mesh, so that the three gears form a train of gears comprising the smallest gear 12, a larger gear 13 and the largest gear 14, effecting a certain ratio of transmission.

On the front end of the main frame 6 is formed a vertical bearing bracket 16 in which is mounted the usual manner a steering post 17 provided on the upper end with a handle bar 18. At the lower end thereof, the post 17 is bifurcated and in the ends of the branches 19 of the bifurcated post is mounted a front axle 21 for a front wheel 22, the latter being disposed between the branches 19.

In order to drive the tricycle mechanism, 109

rotary motion is imparted to the largest gear 14, thru cranks 23. The cranks 23 are fixedly secured upon the shaft of the gear 14, one on each side of the loop frame 7. It is to be noted that the cranks 23 extend in parallelism with each other.

The cranks are operatively connected to the rocking frame B, so as to correlate the rocking and rotating movements of the exercising device. The rocking frame comprises a rocking post 24 having a clevis 26 on the lower end thereof, which is pivotally attached to the main frame 6 at a point intermediate the ends of the frame 6. The pivoting of the clevis 26 allows the rocking of the rocking post 24 about a horizontal axis, namely the pivot of the clevis. On the upper end of the rocking post 24 is pivotally secured a rocking seat 27 intermediate its ends, so as to be fulcrumed on the said upper end of the rocking post 24. The front end of the rocking seat 27 is bifurcated and extends beyond the steering post 17. From the extreme front end of the rocking seat 27 pivotally depend pedal bars 28 carrying foot rests 29 on the lower ends thereof. Each pedal bar 28 has an end of a link 31 pivotally attached to an intermediate point thereof. The links 31 extend rearwardly and have the rear ends thereof pivoted on the ends of arms 32. The other end of the arms 32 are fixedly secured to stub shafts 33, which latter in turn are fixed in the ends of the respective cranks 23. Thus the position of the levers 32 relatively to the cranks 23 is fixed at a certain angle as shown in Fig. 1. The levers 32 are outside of the cranks 23 and are spaced from the ends thereof so as to allow the pivoting of a rocking bar 34 on each shaft 33, and between each crank 23 and lever 32. The rocking bars 34 extend upwardly and the upper ends thereof are pivotally attached to the lower surface of the seat 27. It is to be noted that the rear end of the rocking seat 27 is enlarged to provide ample supporting surface thereat. The rocking bars 34 are urged rearwardly by springs 36. One end of each spring 36 is attached to the respective rocking bar 34, the other end of each spring 36 is secured to a fixed bracket 37, extending upwardly from the frame 6.

In operation the person taking the exercise, sits on the enlarged rear end of the rocking seat 27 and places his feet upon the foot rests 29. Then the weight is shifted upon the feet, so that a downward force is exerted upon the foot rests 29 and pedal bars 28. This causes a forward swinging of the pedal bars 28, pulling the links 31 forwardly. This pull is transmitted thru the levers 32 to the cranks 23, whereby the cranks 23 and the gear 14 is rotated in a clockwise direction viewing Fig. 1. During the upward turning of the cranks 23 the rocking bar 34 is lifted so as to raise the rear end of the seat 27. After the cranks

23 pass the upper dead center, the weight is shifted upon the rear end of the seat 27, by sitting thereon, thus relieving the weight from the foot rest 28. The force thus exerted upon the rear of the seat 27 forces the rocking bar 34 downwardly and turns the cranks 23 further in clockwise direction, and against the action of the spring 36. Thus, the links 31 are pulled rearwardly bringing the pedal bars 28 back to their original position. In order to allow free rocking of the entire frame B, the rocking post 24 is so disposed that it swings rearwardly when the pedal bars 28 are swung forwardly and it swings forwardly when the weight on the seat 27 lowers the rear end of said seat.

It is to be further noted that the seat 27 is swung rearwardly by the post 24 when the rear of the seat is raised, and that it is swung forward when the seat is lowered. Thus the resulting movement of the seat is a horizontal back and forth rocking, and a raising and lowering of the rear of the seat. The position of the members of the rocking frame A, while the seat is raised, is shown in dash 90 and dotted lines in Fig. 1.

The resulting rotation of the gear 14 is transmitted thru gears 13 and 12 to the rear axle 9 thus rotating the traction wheels 11 in a clockwise rotation viewing Fig. 1. If the traction wheels 11 rest on the floor the whole device is driven forward in the manner of tricycles.

In some instances it is desirable to have the exercising device remain in one place, while taking the exercises, and that is accomplished by supporting the traction wheels 11 in an elevated position, off the ground. For this purpose I provide floor brackets 38, upon which are supported the rear bearings 8 in an elevated position. Thus the wheels 11 have no tractive action. When the rear wheels 11 are thus elevated, their momentum is increased by the securing of a weight 39 upon the rim of one or both of the wheels 11, so as to aid in the turning of the crank 23 over the upper dead center.

It is to be understood that when the rear wheels 11 are in elevated position, the device may be operated if so desired, by rotating the rear wheels 11 or axle 9, thereby causing the rocking of the seat 27, so as to impart a forced rocking action to the exercising device, independent of the shifting of the weights by the person taking the exercise. The form of wheel support shown in Fig. 4, comprises rollers 41 on floor brackets 42 which engage the traction wheels 11 frictionally, and this form may be used either to merely elevate the wheels 11 out of tractive position or the rollers 41 may be rotated in any conventional manner so as to drive the wheels 11, thereby effecting the aforementioned forced rocking of the seat 27.

In the modified embodiment of the ex- 130

erciser illustrated in Fig. 3, the general organization of the device is the same as the first described embodiment except that an additional resilient rocking movement is imparted to the rocking post 24. In this embodiment the clevis 26 on the lower end of the rocking post 24 is not pivoted directly to the main frame 6, but it is pivoted to a bifurcated lever 42, the curved rear end branches 43 of which are pivoted upon the rear axle 9. A bolt 44 extends upwardly from the frame 6 and thru the middle of the lever 42 so that the lever 42 is slidable on the bolt 44. A spring 45 is coiled around the bolt 44 pressing against the frame 6 and against the lever 42, so as to urge the lever 42 away from the frame 6. The head 46 of the bolt 44 limits the upward movement of the lever 42. The movement of the lever 42 is fulcrumed around the axle 9. Springs 47 have their ends attached to the respective rocking bars 34 and to the rear of the frame 6 so as to urge the bars 34 rearwardly. The gear 12 is mounted on the axle 9 as in the first described form, but the gears 13 and 14 are journaled in the lever 42 and move therewith. The gears 12, 13 and 14 are always in mesh in spite of the slight pivotal movement of the lever 42. This modified construction provides a resilient support for the seat 27 by reason of the resilient supporting of the lower end of the rocking post 24.

Another embodiment of the invention is shown in Figs. 5 and 6. In this embodiment the frame 51 is bent upwardly at the rear end thereof, having a vertical bearing bracket 52 formed thereat in which is mounted a steering post 53; the latter has the usual fork at the lower end thereof, in which is rotatably mounted a rear wheel 56. In this embodiment the rear wheel is the steering wheel.

The front end of the frame 51 is formed in the shape of a loop 57, on which are bearings 58 extending outwardly from each side thereof. In the bearings 58 is rotatable a front axle 59, to the opposite ends of which are fixedly attached front traction wheels 61. Within the loop 57, a sprocket 62 is fixed upon the axle 59, which is driven thru a chain 63 by a driving gear 64, the latter being mounted within the rear end of the loop 57. A shaft 66 of the gear 64 extends beyond the opposite sides of the loop 57 and has a crank 67 fixed to each end thereof.

It is to be noted here that a bracket 68 extends upwardly from the loop 57, in which is rotatably supported another steering post 69, drivingly connected by horizontal sprockets 71 and a chain 72 to the rear steering post 53, thus allowing the controlling of the rear steering by a steering wheel 73 on the top of the steering post 69 at the front end of the device.

Upon this modified tricycle mechanism, is

a rocker mechanism in which a rocker arm 74 of the shape shown in Fig. 5 is employed. This rocker arm 74 is bent upwardly at both ends so as to form a lowermost bar portion 76, which is held in a comparatively short rocking post 77, the latter in turn being pivoted on a horizontal pin 78, on the frame 51, intermediate the ends of the frame. The rear end of the rocker arm 74 has a seat 79 secured thereto upon which rests the buttock of the party taking the exercise. The front end of the rocker arm 74 has a substantially U-shaped pedal bar 81 pivoted thereto, so that the legs of the bar 81 extend to the respective ends of the cranks 67, and are pivoted to pins 82. The pins 82 are fixed in the outer ends of the cranks 67 and are of sufficient length to receive on the outer ends thereof, levers 83. A lever 83 is fixed upon each pin 82 outside of the pivoted end of the respective legs of the pedal bar 81. Thus the angular relation of the levers 83 to the cranks 67 is fixed. On the end of each lever 83 is the usual foot support 84, upon which rest the feet of the party using the device. It is apparent that the buttock is to the rear of the rocker post 77, while the feet are in the front thereof, consequently the alternate shifting of the weight from the buttock to the feet and vice versa, causes the back and forth and up and down rocking of the rocker arm 74 around the horizontal axis of the rocker post 77. The weight is shifted on the feet until the crank 67 is caused to pass the lower dead center in contraclockwise direction viewing Fig. 5, whereupon the shifting of the weight on the buttock and upon the seat 79 rocks the rocker arm 74 rearwardly, raising the front end thereof, whereby the pedal bar 81 is pulled upwardly, further rotating the crank 67 until it passes the upper dead center. In this manner the rocking motion of the rocker arm 74 and of the post 77 is producing a rotary movement of the sprocket 64 and drives the front wheels 61. The front wheels are usually elevated off the ground, in the manner heretofore set forth, when the exercising device is used in one place, and no propulsion is desired.

Another structural embodiment of my exercising device is illustrated in Fig. 7. The tricycle structure of this embodiment is substantially the same as the tricycle mechanism A, in Fig. 1. It is the rocking mechanism that is modified. A comparatively short rocker post 86 is pivoted on a horizontal pin 87 on the frame 6 intermediate the ends of the latter. From this rocker post 86 extends a rearwardly and upwardly curved rocker arm 88, to the rearmost end of which is secured the usual seat, not shown. To an intermediate point of the rocker arm 88 is pivoted a U-shaped rocker bar 89 the ends of which are pivoted on the short shafts 33 of the cranks 23. A U-shaped pedal bar 91 is

swingably mounted in a bracket 92 which latter extends forwardly from the steering post bearing bracket 16. At the lower ends of the pedal bar 91 are attached the foot rests or supports 29. An intermediate point of each leg of the pedal bar 91 is connected to the outer end of the respective lever 32 by a link 93 in the manner described in connection with the first embodiment of the invention. 10 The links 93 are suitably curved for the transmission of the forward pull from the pedal bar 91. The weight is shifted on the buttock until the crank 23 has passed the lower dead center, whereupon the weight is 15 shifted from the buttock to the feet so as to pull the link 93 forward, thereby to turn the crank 23 in a clockwise direction viewing Fig. 7, until it has passed the lower dead center. Thus the rear traction wheels are 20 rotated, and the exercising device is operated in the manner described.

The leverage of the rocker bar 89 or of the bars 34 is made adjustable by the structure shown in Fig. 8, wherein a lever 94 is interposed between each lower end of the bar 89 and the respective ends of the cranks 23. The lever 94 has an arcuate rear end 96 pivoted on an end of the rear axle 9. The front end of each lever 94 has a plurality of holes 97 therein. The lower ends of the bar 89 may be pivoted in any one of these holes 97, thus an adjustment of the leverage thereof is accomplished. A short link 98 connects each lever 94 to the respective crank 23. One end of 30 each link 98 is pivoted to the outer end of the respective crank 23, while the other end of each link 98 is pivoted to the respective lever 94, intermediate the innermost hole 97 and the fulcrum of the lever 94. The operation of 35 this device is accomplished in the same manner as those of the other embodiments.

It will be recognized that a particularly facile and efficient exercising device is provided, in which a rocking motion is produced by the alternate shifting of the weight from the buttock to the feet of the exercising person, the rocking movement thus produced rotates an inert body, when the traction wheels of the device are elevated off the ground, or 45 the rocking movement is utilized as a driving force to rotate the traction wheels of a vehicle, such as the tricycle mechanism described. The exercising device is simple and rugged in construction and positive in operation; it does not require any careful setting up or adjustment, therefore it readily lends 50 itself to effective application by any person who desires to take such exercise.

Having thus described this invention, what 60 I claim and desire to secure by Letters Patent is:

1. An exercising device comprised of a frame having driven wheels thereon; a seat mounted to rock on a horizontal axis on said frame; a wheel rotating mechanism on said

frame; a crank connected to said wheel rotating mechanism on opposite sides thereof; a lever connected to the seat on one side of its rocking axis and connected to the crank and an articulated lever connected to the seat on the other side of its rocking axis and connected to the crank, whereby the rocking action of the seat thru the levers thereon produces a rotary motion of the crank and wheel rotating mechanism. 75

2. An exercising device comprised of a frame having driven wheels thereon; a seat mounted to rock on a horizontal axis on said frame; a wheel rotating mechanism on said frame; a crank connected to said wheel rotating mechanism on opposite sides thereof; a lever connected to the seat on one side of its rocking axis and connected to the crank and an articulated lever connected to the seat on the other side of its rocking axis and connected to the crank whereby the rocking action of the seat thru the levers thereon produces a rotary motion of the crank and wheel rotating mechanism; a wheel turnably mounted on the frame; and steering means 80 connected to said wheel. 85

3. An exercising device comprised of a frame; a member pivoted in relation to said frame to rock about a horizontal axis and having supports thereon for the buttocks and feet, arranged on opposite sides of the rocking axis of the member; a wheel on said frame adapted to be rotated; and levers connecting the buttocks support and the feet support on the pivoted member to the wheel whereby said wheel will be rotated by the weight of a person, supported by the buttocks and feet on the member, being moved, alternately, back and forth in relation to the pivotal axis of the rocking member to produce a rocking action thereon. 100

4. An exercising device comprised of a frame; a member pivoted in relation to said frame to rock about a horizontal axis and having supports thereon, for the buttocks and feet, arranged on opposite sides of the rocking axis of the member; a wheel on said frame adapted to be rotated; levers connecting the buttocks support and the feet support on the pivoted member to the wheel whereby said wheel will be rotated by the weight of a person, supported by the buttocks and feet on the member, being moved, alternately, back and forth in relation to the pivotal axis of the rocking member to produce a rocking action thereon; and a hand support for the person seated on the member to assist in positioning the body weight to rock the pivoted member. 110

5. An exercising device comprised of a frame; a member pivoted in relation to said frame to rock about a horizontal axis and having supports thereon, for the buttocks and feet, arranged on opposite sides of the rocking axis of the member; a wheel on said 115 120 125 130

frame adapted to be rotated; levers connecting the buttocks support and the feet support on the pivoted member to the wheel whereby said wheel will be rotated by the 5 weight of a person, supported by the buttocks and feet on the member, being moved, alternately, back and forth in relation to the pivotal axis of the rocking member to produce a rocking action thereon; and a tension 10 spring to resist rocking movement of the pivoted member.

6. An exercising device comprised of a frame; a member pivoted in relation to said frame to rock about a horizontal axis and 15 having supports thereon, for the buttocks and feet, arranged on opposite sides of the rocking axis of the member; a wheel on said frame adapted to be rotated; and levers connecting the pivoted member to the wheel 20 whereby said wheel will be rotated by the weight of a person, supported by the buttocks and feet on the member, being moved, alternately, back and forth in relation to the pivotal axis of the rocking member to produce 25 a rocking action thereon.

7. An exercising device comprised of a frame; a member pivoted in relation to said frame to rock about a horizontal axis and having supports thereon, for the buttocks and 30 feet, arranged on opposite sides of the rocking axis of the member; a wheel on said frame adapted to be rotated; levers connecting the pivoted member to the wheel whereby said wheel will be rotated by the weight 35 of a person, supported by the buttocks and feet on the member, being moved, alternately, back and forth in relation to the pivotal axis of the rocking member to produce a rocking action thereon; and a hand support for 40 the person seated on the member to assist in positioning the body weight to rock the pivoted member.

8. An exercising device comprised of a frame; a member pivoted to said frame to 45 rock about a horizontal axis and having supports thereon, for the buttocks and feet, arranged on opposite sides of the rocking axis of the member; an axle journaled in the frame; wheels secured to one end of the frame; a crank on the axle, to be actuated to 50 rotate the axle and wheels; a lever connected to the buttocks support and to the crank; and a lever connected to the feet support and crank, whereby the wheels will be rotated by the weight of a person, supported by the buttocks and feet on the member, being moved, alternately, back and forth in 55 relation to the pivotal axis of the rocking member to produce a rocking action thereon.

60 9. An exercising device comprised of a frame; a member pivoted to said frame to rock about a horizontal axis and having supports thereon, for the buttocks and feet, arranged on opposite sides of the rocking axis 65 of the member; an axle journaled in the

frame; wheels secured to opposite ends of the frame; a crank on the axle, to be actuated to rotate the axle and wheels; a lever connected to the buttocks support and to the crank; a lever connected to the feet support and crank, whereby the wheels will be rotated by the weight of a person, supported by the buttocks and feet on the member, being moved, alternately, back and forth in relation to the pivotal axis of the rocking member to produce a rocking action thereon; a steering post journaled in one end of the frame; and a wheel to be moved by said post. 70

10. An exercising device comprised of a frame having driven wheels and a steering wheel thereon; means to rotate said driven wheels; means to move said steering wheel; a body support pivoted to said frame; a lever pivotally connected to the rear end of the body support and to the wheel rotating means whereby movement of the body support produces a rotary motion of the wheels; and a foot pedal connected to the forward end of the body support and to said wheel rotating means to produce rotary motion of the wheels in conjunction with the rotary motion of the wheels initiated by the body support. 75

11. An exercising device comprised of a frame; a member pivoted to said frame to rock about a horizontal axis and having supports thereon, for the buttocks and feet, arranged on opposite sides of the rocking axis of the member; an axle journaled in the frame; a wheel secured to the axle; a crank on the frame, to be actuated to rotate the axle and wheel, said crank having each of the opposite ends thereof bent to provide legs, each leg having a "throw" arranged at the bend therein and a "throw" arranged at the free end thereof and having the outer end of the leg bent substantially tangentially to the orbit of revolution prescribed by the "throw" on the inner end of the leg; a lever connected to the buttocks support and to one of the "throws" on the leg; and a lever connected to the feet support and the other of the "throws" on the leg, whereby the wheels will be rotated by the weight of a person supported by the buttocks and feet on the member, being moved, alternately, back and forth in relation to the pivotal axis of the rocking member to produce a rocking action thereon. 100 105

12. An exercising device comprised of a frame; a seat pivoted to said frame to rock about a horizontal axis; a foot support lever depending from the forward end of said seat; traction wheels journaled on the frame; a crank and gear mechanism on the frame to rotate the wheels, said crank having each of the opposite ends thereof bent to provide legs, and each leg having the outer end thereof bent at an angle to the inner end thereof; and a link pivotally connected to the outer end of the leg and pivotally connected to the foot support, whereby said link lies in alignment 110 115 120 125 130

ment with the said foot lever to increase the leverage at the start of the application of moving pressure applied to the crank and wheel moving mechanism by the feet resting on the foot support.

13. An exercising devise comprising a stand, a fly wheel rotatably supported thereon having the outer rim thereof spaced from the floor, a member pivoted on the stand to rock about a horizontal axis and having supports thereon for the buttocks and feet arranged on opposite sides of the rocking axis of the member, a rotary element connected to the rocking axis, and drivingly connected to the fly wheel, means on said member to rotate said rotary element as the said member is rocked in opposite directions, whereby rotation is imparted to said fly wheel.

14. An exercising device comprising a stand, a fly wheel journaled therein having the outer rim thereof spaced from the floor, a frame rockably mounted on the stand so as to have a low fulcrum relatively to the floor, a seat arranged above the fulcrum of the frame, leg supports on the frame arranged at a level below the seat, said seat and said leg being on opposite sides of the center of the fly wheel, a crank shaft at the frame fulcrum to be rotated by the alternate rocking of the frame; a wheel on said crank shaft spaced from the floor and connected to the fly wheel to impart rotation to the fly wheel as the crank shaft is rotated.

In testimony whereof, I have hereunto set my hand at San Francisco, California, this 10th day of June, 1929.

JOSEPH D. BELL.
